FEEDING DEVICE FOR CRUSHERS

Oscar C. Gruender, Milwaukee, Wis., assignor to
Nordberg Manufacturing Co., Milwaukee, Wis.,
a corporation of Wisconsin

Application February 17, 1938, Serial No. 190,933

3 Claims. (Cl. 83—10)

My invention relates to an improvement in feeding devices for crushers and is herein shown as applied to a gyratory cone crusher.

One purpose is the prevention of the segregation of fine and coarse particles in the course of the feed to a crusher.

Another purpose is the provision of means for directing the fine particles to the center or the axis of a gyratory crusher.

Another purpose is the provision of a feed device with no moving parts in which the fine and coarse particles are so delivered as to feed uniformly outwardly about the periphery of a feed member mounted on the top of a gyratory crusher head.

Other purposes will appear from time to time in the course of the specification and claims.

I illustrate my invention more or less diagrammatically in the accompanying drawing, where-
20 in is illustrated a vertical section taken along the general axis of a gyratory crusher illustrating the upper portion of the crusher head with the feed spout vertically aligned therewith.

Like parts are indicated by like symbols throughout the specification and drawing. Re-
25 ferring to the drawing, I generally indicates the upper portion of the crusher structure which may be mounted upon or be supported upon any suitable main frame not herein shown. 2 indicates a bowl support which is shown as screw-threaded in relation to the member 1 for pur-
30 poses of adjustment. 3 indicates any suitable bowl liner which may be secured to the mem-
ber 2 as by bolts 4 which pass about lugs 5 ex-
35 tending from the rear face of the bowl liner 3. Since the details do not of themselves form part of the present invention they will not be further described.

6 indicates any suitable crushing head herein
40 shown as a cone. It will be understood that any suitable means may be employed for gyrating the head 6 within the bowl liner 3, in such fashion that the particles fed downwardly into the crushing space defined by the members 3 and 6 will
45 be subjected to a crushing nip. 7 indicates up-
ward supports upon which is adjustably mounted any suitable framework 8 which may be support-
ed as by abutments 9 which may be adjusted and locked in position as by any suitable nuts 10.
50 Mounted upon the framework 8 is a box structure, including side walls, herein shown as vertical and indicated as at 11, and any suitable bottom 12 having an aperture 13 out of line with the central axis of the crusher which is indicated at X.
55 14 is any suitable spout or chute adapted to

deliver the material as shown at 15, 16 toward a part of the bottom 12 which is out of line with the aperture 13. As is shown in the drawing, the coarse particles 15 tend to segregate from the fine particles 16 and the fine particles do not tend to travel as far as the coarser particles. There is, therefore, a concentration of fine particles as at 17 adjacent one edge of the aperture 13. In connection with the aperture 13 I illustrate a down spout 18 to which is connected an inclined spout section 19 which in turn communi-
10 cates with a generally vertical spout 20. The spout 20 is axially generally aligned with the axis X of the device in such fashion as to deliver the material directly downwardly upon any suitable feed plate or member 21 upon the head 6.

The relation of the location of the spout 18 to the concentration of fine particles 17 is such that fine particles 17 tend to flow downwardly along one wall of the member 18 as at 22. The off-
20 setting of the spout as at 19 causes this roughly defined column of fine particles 22 to fall directly downwardly along the axis of the device. The coarser particles tend to build up as at 23 and are gravitationally projected as at 24 toward the lower wall 25 of the offset portion 19. They then tend to ricochet laterally into the spout 20 and to disperse themselves roughly throughout the spout area. They interfere with the columnar formation of the fines 22. They mix the fine and the coarse particles together. So far as the fine particles remain concentrated on the axis of the device, they land adjacent the middle of the plate 21.

In either event, there is a tendency for the coarse particles to spread throughout the area of the spout 20 and to drop on the plate 21 pretty well throughout its area. As the plate 21 gyrates in unison with the gyration of the head 6, the fine particles are fed outwardly toward and over the wall of the plate 21 uniformly throughout its periphery, and the coarse particles are also outwardly uniformly fed throughout the outer periphery of the plate 21 and there is no tendency for the coarse and fine particles to be segregated to one side or other or to any particular part of the crushing cavity.

Additional feed directing means may be employed, for example the hopper 26 shown as mounted on the head 6 surrounding the feed plate 21. What I consider as particularly important in connection with my invention, however, is the equalization of the feed of the particles over the edge of the plate 21 and into the crushing cavity. In practice, in employing 55

a crusher of the type herein shown, if the fine and coarse particles are segregated in such fashion as to permit an excess of fines to be fed to one side of the crushing cavity, the result is 5 an uneven and relatively inefficient operation of the device. Without going into the details of why it should be so, it is a fact, as established by practical experience, that a uniform distribution of the fine and coarse particles about the 10 crushing cavity is very important in practice and promotes efficient and economical crushing and reduces the strain on the crushing device.

It will be realized that whereas I have described and shown a practical and operative device, 15 nevertheless many changes may be made in the size, shape, number and disposition of parts without departing from the spirit of my invention. I wish, therefore, that my description and drawing be taken as in a broad sense illustrative and 20 diagrammatic rather than as limiting me to the precise structure herein described and shown.

It will be understood, of course, that the box 11 may be of a variety of shapes although I find it practical to make it square. Similarly, the 25 down spout structure may be of a variety of cross sections. I may, for example, have the lower portion 20 round so that its lower edge conforms generally to the periphery of the plate 21, being however spaced substantially there- 30 within.

I claim:

1. In a feed device for crushers, having a generally upright axis, a normally fixed feed box, an inclined chute, adapted to deliver particles of mixed sizes into said feed box along an inclined path, whereby the fine and coarse particles tend to segregate, a down spout extending downwardly from the bottom of said box and located adjacent but out of vertical alignment with 35 the zone of delivery of the particles delivered from said chute, one edge of said down spout being adjacent the zone of maximum concentration of the fine particles and also being generally aligned with the general axis of feed of particles 40 to the crusher, a lower spout member generally concentric with the axis of the crusher, and an 45

inclined section connecting said lower spout member with said first mentioned down spout, said inclined section including a wall located at the zone of gravitational delivery of the coarse particles downwardly over said edge of the down spout, 5 and adapted to direct said falling particles inwardly across the general axis of feed of the fine particles downwardly over said edge.

2. In a feed device for gyratory crushers having a generally upright axis, a normally fixed feed box vertically aligned with and above the crushing head of the gyratory crusher, conveying means adapted to deliver particles of mixed sizes into said feed box, at an area located at one side of the axis of the crusher, an eccentric down spout extending downwardly from the bottom of said feed box and in communication therewith, the edge of said down spout nearest the area of delivery of the conveying means to the feed box being adjacent the axis of the crusher, a lower spout member generally concentric with the axis of the crusher, and a section connecting the lower spout member with the first mentioned down spout, said section having a portion adapted to receive the larger particles and to return them toward the axis of the crusher and of the lower spout member. 10 15 20 25

3. In combination with a crushing head having a generally upright axis, a normally fixed feed receiving member vertically aligned with and above said crushing head, and having a feed receiving and arresting surface, means for feeding particles of mixed size to said arresting surface, an eccentric down spout extending downwardly from and in communication with said arresting surface, a side of said down spout being adjacent said surface and located generally on the axis of the crushing head, the body of the spout extending substantially outwardly from the axis of the crushing head on the side of said axis opposite to said arresting surface, a lower spout member generally concentric with the axis of the head, and an intermediate spout section connecting said two spouts. 30 35 40 45
